UNITED STATES PATENT OFFICE.

HERBERT A. HUMMER, OF FRENCHTOWN, NEW JERSEY.

IMPROVEMENT IN COOKING-STOVES.

Specification forming part of Letters Patent No. 142,467, dated September 2, 1873; application filed April 12, 1873.

To all whom it may concern:

Be it known that I, HERBERT A. HUMMER, of Frenchtown, in the county of Hunterdon and State of New Jersey, have invented a new and valuable Improvement in Cooking-Stoves; and I do hereby declare that the following is a full, clear, and exact description of the construction and operation of the same, reference being had to the annexed drawings making a part of this specification, and to the letters and figures of reference marked thereon.

Figure 1 of the drawings is a representation of a vertical longitudinal section of my cooking-stove. Fig. 2 is a horizontal section of the same. Fig. 3 is a vertical transverse section of the same.

This invention has relation to cooking-stoves; and consists in the construction and novel arrangement of the sliding fire-box, the flue in rear thereof with its damper, the chambers at the ends of the fire-box in the stove-wall, with the deflecting-partitions, register-openings, and pipes for conveying the hot air to the rear of the stove.

In the accompanying drawings, the letter A designates the oven of the stove; B, the smoke-flues; C, the ash-pan. The front wall of the oven is beveled downward to the base of the fire-box, and is continued from this point at a greater inclination, as shown at a, to the ash-pan. D indicates a brace, which supports the top of the stove from the top of the oven. E represents the fire-box. This is not attached to the stove-wall, but is an independent structure, consisting of the two end walls b b, the rear wall c, the bottom or sliding grate e, and the front or fixed grate k. The end walls b are provided with flanges d, extending outward from their upper edges, and resting upon ledges n of the stove-wall. Between the fire-box wall b and the stove-wall on each side are located the plates h, which may be secured to the stove-wall, and are provided with the deflecting flanges or partitions l, extending to the stove-wall. The air-chambers m, formed between the plates h and the stove-wall, are thus divided into communicating-passages u, through which the air-currents received through the register-openings v pass in a deflected or zigzag manner alternately upward and downward until they reach the openings of the hot-air pipes z, which are

laid under the overhanging ledge of the top plate of the stove, extend to the rear, and open into the upright hot-air pipe L. The bottom grate e is hung at the back, the front being held up by the lever r resting upon the horizontal bar a', which extends toward each other from the depending arms b' of the front or swinging grate. The rear end of the lever r is stepped in the rear wall of the fire-box, and by vibrating it the bottom grate is shaken to and fro endwise. The bottom grate is dumped by separating the bar a', so that the lever r can pass through. This grate will then fall against the lower slant a of the front oven-wall. The fingers c' of the front grate are designed not to reach down to the level of the bottom grate, a space, e', being left between for convenience in cleaning out clinkers and other obstructions from the fire-box. The fire-box can be drawn forward on the slides d. When this is done a flue, F, is opened between the rear wall of the fire-box and the oven-wall, by means of which the draft of the fire may be checked or regulated, and the dust caused by raking may be drawn inward through the flues of the stove, instead of being suffered to escape out into the apartment. G indicates a slide-damper, located on the brink of the front oven-wall, and arranged to slide forward for the purpose of closing, more or less, the flue F, and thus regulating the draft through the same. An arm, H, extends back from the slide G, and is pivoted to the oven-top at v', and, extending through a slot in the stove-wall, serves as a means by which the slide G may be adjusted. From the front of the top of the stove a curved wall, M, extends downward and rearward, joining the front wall of the stove, and extending over the upper edge of the front grate in the form of a flange, m', serving as a guide for the supply of coal. The removable magazine N consists of an elliptical or elongated tube, which is designed to fit the opening n' in the top plate in the manner of a wash-boiler, except that it is bottomless. A top, z', is used with the magazine, which, when the magazine is not in use, may be employed to close the opening n' in the top plate of the stove.

What I claim as new, and desire to secure by Letters Patent, is—

1. The combination of the suspended sliding

fire-box E, having the outwardly-extending flanges d, resting upon the ledges n of the stove-wall, and the slide-damper G, having the forked arm H and pivoted lever k, extending through the stove-wall, for regulating the opened flue F between the rear wall of the fire-box and the oven-wall, operating substantially as specified.

2. The fire-box E, having the fixed front grate k, with short fingers c' and long arms b', and the longitudinally-sliding bottom grate e, pivoted in rear, in combination with the hinged bar a and the lever r, substantially as specified.

3. The arrangement of the air-chambers m at each end of a fire-box only, next to the

stove-wall, and having the deflecting flanges or partitions l and communicating-passages, in connection with the register-openings v and hot-air pipes z, for the purpose mentioned.

4. The arrangement of the hot-air pipes z immediately under the ledge of the top plate of a stove, and extending around the sides and rear end thereof, and communicating with the air-chambers m and pipe L, for the purpose mentioned.

In testimony that I claim the above I have hereunto subscribed my name in the presence of two witnesses.

Witnesses: H. A. HUMMER.
